Inventor
Charles D. Brooks.
By his Attorney J. O. Fowler.

UNITED STATES PATENT OFFICE.

CHARLES D. BROOKS, OF BROOKLYN, NEW YORK.

COMPOSITE STRUCTURE.

Application filed March 16, 1920. Serial No. 366,444.

To all whom it may concern:

Be it known that I, CHARLES D. BROOKS, a citizen of the United States, and resident of Brooklyn, in the county of Kings and 5 State of New York, have invented a certain new and useful Composite Structure, of which the following is a specification, the same being a full, clear, and exact description of the invention, such as will enable 10 others skilled in the art to which it appertains to make and use the same.

This invention relates to laminated structures, as vessels for containing material,—as a sectional watertight box or casing, or 15 chest-like receptacle which may be used in building, as a caisson of preferably watertight construction, or which may be employed for holding liquids, as a tank,—or which may be utilized for any other suitable 20 and approved purposes or uses to which they may be found to be adapted and where a laminated structure is desired. The various sections of the composite material may be and in use preferably are rigidly held together by any approved tying or binding 25 devices in order that the entire structure shall present an unbroken wall surface.

With the above and other useful objects and purposes in view, which will be described below, the invention consists in the construction, arrangement and operation of parts hereinafter set forth: In the drawings, illustrative of one embodiment of the 30 invention, which accompany and form a part of this specification, Figure 1 is an elevation of a structure made according to my invention;

Figures 2 and 3 are plan views of the same;

Figure 4 is a section on the line 4—4, Figure 1;

Figure 5 is an elevation of my bolt and nut;

Figure 6 is a view in elevation of my tool for drawing the nut on the bolt; and

Figure 7 is an elevation of my tool for drawing the bolt into the wooden strips.

In one example of my invention, the same comprises the use of a structure consisting 50 of a plurality of sectional side pieces or ribs 1 forming a laminated structure which may either be made in cylindrical construction or of rectangular or other conformation as indicated by the numeral 10 in the latter case. The structure preferably has a bottom portion denoted respectively by the nu-

meral reference characters 2 and 2' and may be used with or without a lid or other enclosing top or cover.

In cases where the side pieces or ribs comprise a plurality of horizontally disposed parts, they are preferably formed at the junction or abutment thereof with engaging or interlocking devices, as the shouldered portions 4. At various points along the 60 faces of the side pieces or ribs, I form interiorly disposed recesses or orifices 1' or 10', the said recesses of any two abutting faces of the side pieces or ribs being in alignment and having centrally disposed communicating bores to contain bolts 3, the heads of the 65 bolts resting in one of the said recesses—or being drawn up into the wooden strip by a tool as hereinafter described—and the nuts 3' thereof lying in the other recess. 75

These bolts and nuts constitute tying or binding devices whereby the said two abutting side pieces or ribs are rigidly held together. I preferably arrange the respective recesses and bolts so that the bottom 2 or 2' 80 shall be rigidly attached to the superposed ribs or side pieces thereby.

The said superposed side pieces or ribs are secured to the ribs or side pieces lying on the same by the use of similar recesses and 85 bolts, which may be staggered with respect to the ones first described. The last named second layer and the third superposed ribs or side pieces, which two form another pair, are similarly tied together, and the same 90 plan of construction is preferably followed until the top of the vessel has been reached.

It will be noted that the various bolts are set in their proper position as the various 95 layers or sections are being built up, and the nuts tying a pair of layers together are secured in place before the nut for the next higher layer is placed in position. The various layers are thus built up in pairs, each layer of section serving as the top of one 100 pair and as the bottom of the next higher pair. Obviously the bolts may serve to tie three or more layers together, instead of a single pair, if desired.

As the recesses and bolts lie in the interior of the ribs or side pieces, they are entirely concealed from view and both the outer and inner faces of the receptacle will present unbroken wall surfaces, as the interstices between the various layers are closed by the 110 tightened bolts and nuts.

By the construction of a vessel in this

manner a watertight tank or caisson may be formed without the employment of packing between the various layers of the same, as even if there were any interstices between the layers through failure of properly tightening the bolts and nuts, the dampness of the ground or that of the liquid contained therein would serve to make tight joints in every part of the unbroken wall of the receptacle. My invention may, manifestly, be utilized in connection with flat layers or laminations of various materials.

The orifices at the upper and lower faces of the structure may be filled with sealing wax, melted lead or other desired sealing material in order to avoid any tampering with the tank or other laminated device.

As stated, the superposed sections or laminations may be tied or bound together in any suitable or approved manner. As one example of a convenient way of securing the various layers rigidly together, the bolts 3 preferably have heads 3² formed with fins 3³ in order to prevent rotation thereof. The said bolts are preferably inserted in bores made in the superposed wooden strips and being slightly less in diameter than that of the bolts, and the shank of each of the latter is driven through the said bore, after which an internally threaded tool 5 may be placed on the said shank, whereupon by rotating the tool by its handles 5', the head of the bolt will be drawn up into the wood.

The slotted nut 3' may now be set on the end of the shank and drawn down by the tool 6 having means to engage the said slot, which tool may be turned by means of a wrench 7 to force the nut down as far as possible.

It is obvious that my composite structure may be utilized in the manufacture of other articles than containing vessels, as for example, in any structure comprising superposed layers or sections of strips or slabs—whether made of wood, or metal, or otherwise—as the invention resides principally in

the formation of laminated material rigidly held together so as to constitute a solid mass.

I wish it to be understood that I do not desire to be limited to the particular use or the exact details of construction shown and described, for obvious modifications will occur to persons skilled in the art.

What I claim as my invention is:—

1. In a device of the class described, a structure comprising a plurality of horizontally disposed sections, and a plurality of detachable devices of equal length for tying each abutting pair of sections together, some of said devices being staggered as regards the remainder, one pair of sections entirely enclosing therein tying devices, and one of said pair and an adjacent section forming another pair of sections entirely enclosing therein a staggered series of tying devices.

2. In a device of the class described, a structure comprising a plurality of superposed sections, each abutting pair of sections being formed with aligned communicating recesses and one of said pair and another adjacent section forming another pair made with aligned communicating recesses, staggered as respects the former recesses, and means of equal length entirely enclosed within and detachable from said recesses to tie the said sections together.

3. In a device of the class described, a structure comprising a plurality of superposed sections, each abutting pair of sections being formed with aligned recesses communicating only with said pair of sections, and detachable means of equal length enclosed entirely within said recesses to tie the said sections together, the tying means connecting the sections of each pair being staggered both vertically and horizontally with respect to the tying means connecting the sections of other pairs.

Signed at Buffalo, in the county of Erie and State of New York this 21st day of February A. D. 1920.

CHARLES D. BROOKS.
